DOOR PLATE FOR A CHAIN BOLT

Philip J. Walther, Newington, Conn., assignor to
 Emhart Corporation, Bloomfield, Conn., a corpora-
 tion of Connecticut

Filed Oct. 11, 1968, Ser. No. 13,954

Term of patent 14 years

Int. Cl. D8—03
 U.S. Cl. D8—137

FIG. 1

FIG. 2

FIG. 1 is a front elevational view of the door plate for a chain bolt, the broken lines being for illustrative purposes only.

FIG. 2 is a sectional view taken along the line 2—2 of FIG. 1.

I claim:

The ornamental design for a door plate for a chain bolt, as shown and described.
